FLASHGUN

Robert L. Pennock, Jr., Denver, and Raymond J. Breer, Littleton, Colo., assignors to Heiland Research Corporation, Denver, Colo., a corporation of Colorado

Application December 7, 1950, Serial No. 13,312

Term of patent 7 years

(Cl. D61—1)

To all whom it may concern:

Be it known that we, Robert L. Pennock, Jr., and Raymond J. Breer, citizens of the United States and residents of Denver, city and county of Denver, and Littleton, county of Arapahoe, State of Colorado, whose postoffice addresses are 972 South Gilpin Street, Denver, Colorado, and 206 Cedar Street, Littleton, Colorado, respectively, have invented a new, original, and ornamental Design for a Flashgun, of which the following is a specification, reference being had to the accompanying drawing, forming part thereof.

Figure 1 is a perspective view of a flashgun showing our new design;

Figure 2 is a side view of the reflector mount portion from the flashgun shown in Figure 1; and

Figure 3 is a top plan view of the reflector mount portion from the flashgun shown in Figure 1.

The dominant features of my design reside in the portions shown in full lines.

We claim:

The ornamental design for a flashgun, as shown and described.

ROBERT L. PENNOCK, JR.
RAYMOND J. BREER.
